WASHING MACHINE

Walter K. Voss, Davenport, Iowa

Application May 25, 1931, Serial No. 539,751

2 Claims. (Cl. 74—75)

The present invention relates to washing machines and more in particular to a novel drive or operating mechanism therefor. Among the objects of the present invention is to provide a 5 novel and simplified driving mechanism for a washing machine.

Another object of the invention is the provision of an adjustable mounting for a vertically disposed motor or prime mover whereby the position of the motor may be shifted to adjust the tension on the belt for driving the operating mechanism. The present embodiment discloses and contemplates a simple adjusting device for shifting or changing the position of the motor 10 whereby to draw more taut or loosen the tension on the belt which is driven by the motor and drives a pulley on the housing.

A still further object of the invention is to provide a compact washing machine driving and 20 operating mechanism mounted below and suspended from the tub whereby to eliminate the platform or other base or mounting adjacent the bottom of the machine so as to provide additional clearance space below the tub and operating 25 mechanism.

A general object is to provide a construction of maximum simplicity, efficiency, economy and ease of assembly and maintenance, which embodies few operating parts arranged so as to be 30 readily accessible for inspection, repair or replacement of parts.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and 35 alternative constructions falling within the spirit and scope of the invention as expressed in the appended claims.

Referring to the drawings:

Figure 1 is a view in perspective of the washing machine.

Fig. 2 is a vertical sectional view taken on the irregular line 2—2 of Fig. 3.

Fig. 3 is a fragmentary vertical cross-sectional view through the tub and gear casing or housing, 50 the operating mechanism being disclosed in side elevation.

Fig. 4 is a fragmentary view in vertical cross-section taken on the line 4—4 of Fig. 2.

Fig. 5 is a vertical cross-sectional view taken 55 on the line 5—5 of Fig. 2, and disclosing means

for adjusting or shifting the position of the motor.

Referring more particularly to the drawings, the embodiment selected to illustrate the invention is shown as comprising a washing machine tub 1 having a cover or closure 2 and supporting legs 3, 4 and 5, equally spaced around the circumference of the tub, and the legs 3 and 5 connected to the tub by any suitable means. A wringer mechanism 6 is disclosed as rotatably mounted 10 upon a sleeve or standard 7 suitably positioned on a gear housing or casing 8.

This gear housing or casing 8 comprises an upper section 9 and a lower section 10, the latter being supported by the leg 4 of the machine. 15 The means for supporting the housing by the leg 4 includes a bracket 11 provided with a pair of ears or flanges 12 adapted to be connected to the legs by suitable attaching means 13 such as bolts or the like. The upper section 9 of the housing 20 or casing 8 is provided with a tubular boss 14, which is preferably formed integrally therewith but, of course, may be connected in any suitable manner thereto. This boss is provided with an annular flange 15 adapted to seat against and be 25 connected to the bottom of the tub 1 and to an inverted cup-shaped bearing member 16 within the tub. For this purpose, the bearing member 16 is provided with a plurality of spaced lugs or bosses 17 adapted to receive bolts or other attaching means 17a passing through the annular flange of the boss 14, through the bottom of the tub 1, and into the lugs or bosses 17. The bearing 30 16, together with the tubular boss 14, thus provides an enclosed, watertight compartment, 35 portions of which are on opposite sides of the tub bottom and are in communication through an enlarged aperture 16a provided in said bottom.

A center pole or agitating shaft 18 passes centrally through the boss 14, aperture 16a and bearing 16, and through an upwardly extending sleeve 19 threadedly engaged in the upper portion of the bearing 16. Detachably mounted upon the bearing 16 is a sleeve 20 provided with longitudinally extending grooves 21 on opposite sides 45 thereof and extending for substantially the full length of the same. This sleeve 20 extends above the top of the inner sleeve 19 and is keyed or otherwise secured to the shaft or center pole 18 so as to rotate therewith, the inner sleeve 19 of 50 course being held stationary on the bearing member 16. The upper ends of the sleeves 19 and 20 are disposed above the highest water level thereby to seal the assembly against the escape 55 of water from the tub.

The lower end of the shaft 18 is journalled in a socket bearing 18^a which preferably is formed integrally with the lower housing section 10. Thus, the shaft is supported by the two widely spaced bearings 16 and 18^a, respectively, disposed substantial distances above and beneath the bottom of the tub. A decided advantage is obtained thereby in that the shaft is rigidly and sturdily supported and is amply capable of withstanding any lateral stresses applied thereto in the operation of the machine.

Within the tubular boss 14, which encloses and protects the portion of the shaft 18 intermediate the tub bottom and the upper gear housing section 9, is means for preventing the passage of water along the shaft into the housing. To this end, the upper section 9 within the boss 14 has an outstanding circular flange 14^a thereon defining the aperture through which the shaft extends into the housing. This flange, together with the lower portion of the boss, forms an annular, U-shaped channel 14^b completely surrounding the shaft. The shaft carries a downwardly sloping and outwardly flaring sleeve 14^c arranged with its peripheral edge overlying the channel 14^b and disposed between the flange 14^a and the boss 14. A small aperture 14^d in the boss 14 provides a drain for water accumulations. Hence, the gear housing is positively sealed against the entrance of all condensate, seepage, or other accidental water.

A floating dolly or agitator 22 is provided with lugs or projections (not shown) adapted to slidably engage in the groove 21 in the sleeve 20, thereby permitting automatic adjustment of the agitator or dolly in accordance with the quantity of washing fluid in the tub. The dolly is provided with a handle 23 permitting the same to be manually raised and removed from the sleeve 20 whenever desired. Blades 24 are provided on the agitator or dolly for swishing the clothes or material operated upon through the cleansing fluid. The present construction of agitator or dolly and the sleeve 20 upon which the same is slideable and by which the dolly or agitator is operated, is more fully disclosed in my pending application Serial No. 438,334, filed March 24, 1930, now Patent No. 1,869,590, granted August 2, 1932.

The means and mechanism for driving the center pole or dolly shaft 18 and for oscillating the same, comprises a vertically disposed motor or prime mover 25 provided with a source of current supply 26 and a switch 27 conveniently located on the leg 5. The shaft 29 of the motor is extended a substantial distance above the motor and is provided with a pulley 28 keyed thereto and rotatable therewith. This pulley, in turn, drives a belt 30, the latter in turn driving a large pulley 31 mounted on a shaft 32 and keyed thereto so as to rotate the same. Alined bosses 33 and 34, formed on and extending outwardly of the sections 9 and 10 of the gear housing respectively, provide bearings for the shaft 32. Located within the housing 8 and keyed to the shaft 32, is a pinion 35 meshing with and driving a large gear 36 keyed to a shaft 37 mounted in bearing members 38 and 39 formed similarly to the bearings 33, 34. The bearing member 38 is arranged to seat within the sleeve 7 for the wringer drive, and the shaft 37 extends upwardly through the sleeve 7 to form the drive shaft for the wringer mechanism.

An annular flange or boss 40 is eccentrically formed on the gear 36 and is provided with a

plurality of inwardly projecting ears or lugs 41 (Fig. 4) adapted to receive bolts or the like 42 provided with washers for seating and maintaining an eccentric strap 44 around the flange or boss 40. This flange or boss 40 is also provided with a lug 45 (Fig. 2) through which the shaft 37 passes. The eccentric strap 44 is provided with a connecting arm or rod 46 which is attached to a crank arm 47 by means of a pivot pin 47^a. The crank arm 47 is provided with a bearing member or sleeve 48 to receive the agitator drive shaft 18. The sleeve 48 is rigidly connected with the shaft 18 by such means as a pin 49. The arrangement of these parts is such that, as the gear 36 and the eccentric boss 40 rotate, the strap 44 describes a circular orbit which movement, through the rod 46, crank arm 47 and sleeve 48, produces an oscillatory movement of the shaft 18 to actuate the dolly. The limit of the movement of the crank arm is shown in dotted outline in Fig. 2 of the drawings.

The means for adjustably mounting the motor assembly is as follows: The motor 25 is provided with a base 50 having a rod or pin 51 passing therethrough and seated within bearings 51^a on the base. A bracket member 52 (Figs. 1 and 3) is mounted or formed on the lower section 10 of the gear housing 8 and is provided with an upper bearing or lug 53 and a lower bearing or lug 54, through which the rod or pin 51 passes. By reason of this construction, it will be readily seen that the motor or prime mover is pivoted and adjustably positioned on the pin 51, the purpose being to adjust the tension on the belt 30 by shifting the position of the motor 25 and its pulley 28. The invention contemplates a simple and efficient means of adjusting the position of the motor, the same including a bolt or threaded member 55 (Fig. 5) threadedly engaging in a lug 56 on the lower section 10 of the gear housing. The end of the bolt 55 is arranged to engage a part of the motor base 50 at a point remote from the pivotal axis thereof. By merely adjusting the bolt 55, it is, therefore, possible to swing the motor to adjust the tension of the belt 30. A lock nut 58 prevents shifting of the member 55 after it has once been manually adjusted.

From the above description and the disclosure in the drawings, it will be readily seen that I have provided a novel and efficient direct drive for the center pole or shaft 18 which drives the washing machine dolly and the shaft 37 for the wringer drive. The upper end of the shaft 37 carries preferably means for connecting the shaft with the wringer mechanism such as a coupling member 59 having a cut-out 60 adapted to receive pins or other coupling means on the end of a stub shaft which drives the wringer mechanism. The coupling member 59 is provided with a bearing 61 adapted to seat conformably within the sleeve 7 for the wringer mechanism. By reason of this direct drive construction of both operating shafts, few parts are necessary whereby to eliminate to a great extent the wear and tear incident to a drive mechanism, as well as to eliminate any clutch constructions.

In order to prevent injury to the clothing or person of the operator, a shield 62 (Fig. 3) encompasses the pulleys and belt and is formed on or connected to the upper section 9 of the gear casing or housing.

I claim as my invention:

1. In a washing machine including a tub and a plurality of supporting legs; a simplified com-

5 compact power transmission mechanism embodying in combination an elongated flattened gear housing in a plane below the tub, supported at one end by said tub and at the other end by one of said legs; a rotary dolly shaft extending downwardly from said tub into said gear housing and having laterally projecting rigid means on the part within said housing engageable for rotating said shaft; means within said housing including a large rotatable gear having an eccentric boss on one face and a connecting rod of substantial length in operative engagement at one end with said eccentric boss and at its other end with said rigid means so as to impart rotational movement to said shaft upon rotation of said gear; a wringer drive shaft arranged coaxially and rigidly with said large gear whereby the shaft is continuously rotated upon rotation of the gear; a motor adjustably mounted on said gear housing on a vertical axis and having a drive shaft extending upwardly toward the bottom of said tub, a friction pulley and belt drive in a plane between said large gear and the bottom of said tub and operatively connecting said motor shaft

and said large gear; and means for adjusting the position of said motor relative to said housing to adjust the tension of said belt in order to insure a uniform transmission of power.

2. In a washing machine including a tub and supporting means therefor, a dolly shaft extending vertically below the bottom plane of said tub, a vertical wringer shaft on one side of said tub and also extending below the bottom plane of said tub, power transmission mechanism including a gear housing removably supported below said tub with the ends of both of said shafts operatively connected with the mechanism within the housing, a motor-supporting bracket mounted on said housing, an electric motor having means providing a movable connection with said bracket, and means including a drive connection between said motor and said power transmission mechanism adjustable by movement of said motor relative to said housing, said motor and power transmission mechanism together forming a compact unit adapted to be installed or removed as an entity. 5 10 15 20

WALTER K. VOSS.
